SAMUEL B. JEROME, OF NEW HAVEN, CONNECTICUT, ASSIGNOR TO SAMUEL PECK & CO., OF SAME PLACE.

Design No. 4,278, dated August 9, 1870.

DESIGN FOR A CLOCK-CASE FRONT.

The Schedule referred to in these Letters Patent and making part of the same.

To whom it may concern:

Be it known that I, SAMUEL B. JEROME, of the city and county of New Haven, and State of Connecticut, have invented a new and original Design for a Clock-Front, of which the following is a specification, reference being had to the accompanying drawing, in which—

Figures 1 and 2 represent front views of the clock-front; and

Figures 3 and 4 sections of said front, on the lines xx and yy .

The clock-front, in which my invention consists, is composed of the wooden frame a , divided into two compartments, in the upper of which is set a front, b , of plastic composition, usually made of equal parts of shellac and resin, with sawdust or fibrous material enough to give the composition toughness, and coloring matter, to impart such color to it as may be desired.

This plastic-composition front is formed with a circular opening, corresponding to the dial-plate of the clock, and is molded with ornamental designs upon its

surface, with either a plain or gilt finish, as desired. It is also covered by a glass plate, c , to exclude the dust.

In the lower compartment of the frame a is secured a tablet, d , of plastic composition, which is also covered by a glass plate, e , and is provided with an ornamental center-piece, f , formed by pressing up in relief the composition into the desired design, or by setting a picture, g , in an opening left for the purpose in the tablet. The tablet is, besides, molded or impressed with ornamental figures, as shown.

What I claim, and desire to secure by Letters Patent, is—

The design for a clock-front, as herein shown and described.

In testimony whereof I have hereunto set my hand this 8th day of June, 1870, before two subscribing witnesses.

SAMUEL B. JEROME.
